UNITED STATES PATENT OFFICE.

ERNEST S. HOYT, OF PEPIN, WISCONSIN, ASSIGNOR OF TWO-THIRDS TO HENRY S. HOYT AND TUSCO MCKINLEY HOYT, BOTH OF PEPIN, WISCONSIN.

OIL BURNER.

Application filed March 26, 1923. Serial No. 627,685.

To all whom it may concern:

Be it known that ERNEST S. HOYT, a citizen of the United States, residing at Pepin, in the county of Pepin and State of Wisconsin, has invented certain new and useful Improvements in Oil Burners, of which the following is a specification.

In carrying out the present invention it is my purpose to provide an improved oil burner that will embrace the desired features of simplicity, durability and efficiency, the device comprising relatively few parts and these so correlated as to reduce the liability of derangement to a minimum.

A further purpose of my invention resides in the provision of such a burner wherein the burner pan or tray may be readily removed from the main body of the burner for facilitating the replacement of parts for the cleaning of the same whenever desirable.

A still further purpose of the invention is the provision of such a device that may effectively burn the less expensive grades of fuel, it being herein well to note that there is mixed with this fuel a charge of steam which will effectively reduce the fuel consumption and at the same time provide as high a degree of heat as would otherwise be obtained through the burning of more expensive grades of fuel.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views, and wherein:

Figure 1 is a side elevational view of my improved oil burner;

Figure 2 is a detail cross sectional view thereof;

Figure 3 is a longitudinal cross section upon the line 3—3 of Figure 1; and

Figure 4 is a cross section of a modified form of burner nozzle.

Referring to the drawings in detail, 5 designates the main body of the burner which is in the form of a hollow goose neck having one end reduced at 6 for providing a shoulder 7.

The burner pan or tray is designated 8 and is of a well known construction, this pan or tray 8 being formed with an extension 9, the end of this extension being in turn formed with a sleeve or collar 10. 60 This sleeve or collar 10 is positioned over the said reduced end 6 of the goose neck body 5, the upper edge thereof having close contact with the said shoulder 7. Any desirable means may be provided for securing the same to the reduced end of the body 5, the same being preferably in the form of a set screw 11.

Upon the extension 9 at the pan or tray 8 is a water tank 12, this tank being equipped 70 with an outlet pipe 13 that extends upwardly and forwardly and is coiled at 14. Secured at one end within an opening of the said tank 12 is a pipe section 15, the opposite end thereof being provided with 75 a coupling 16 whereby the said pipe section may be connected to a source of water supply.

The top wall of the goose neck body 5 adjacent one end thereof is provided with 80 an opening within which is a tube 17, it being noted from a consideration of Figure 2 that the lower end of this tube terminates at a point inwardly of the front end of the body.

The free end of the said outlet pipe 13 is secured in any manner desirable in the upper end of the tube 17 and secured within an opening upon one side of the tube and adjacent its upper end is one end of 90 an oil pipe 18, this pipe being provided with a coil portion 19 as well as a coupling 20 upon its opposite end. This coupling 20 is adapted for connecting the oil pipe 18 to a source of fuel supply.

The pan or tray 8 is provided with a drain pipe 21 and in view of the above description it will, of course, be apparent that air is adapted for passage through the goose neck body 5 and that when the tank 5 is filled with water the heat from the burner will effectively generate steam, after which the same is mixed with the oil in the tube 17, the coil portion 19 within the pipe 18 facilitating vaporization of the fuel.

In the form of the structure as illustrated in Figure 4 of the drawing, the nozzle tube is indicated at 17' and is connected with a fitting 25 which is adapted to pass through the top of the body 5,

hereinbefore described. The fitting 25 is provided with a nipple 26 to which the pipe 18, hereinbefore described, may be connected. A nipple 27 is disposed centrally 5 of the fitting 25 and the nozzle 17' and is spaced from both of the said parts. The upper end of the nipple 27 communicates with a pipe 13, hereinbefore described, and which admits the vapor, steam or water 10 into the burner nozzle. By reason of this structural arrangement, the vapor, steam or water may be carbureted at the nozzle by mixture with the oil or oil vapor, and when the mixture is thus enriched, an intensely hot flame may be produced upon 15 the pan or tray 8.

Although I have herein shown and described the preferred embodiment of the present invention, it is nevertheless to be understood that minor changes may be made therein, without departing from the spirit and scope of the invention as claimed.

Having thus described my invention, what I claim as new and desire to secure 25 by Letters Patent is:

1. A burner comprising a tray, a goose-neck body mounted thereon and having one of its ends communicating with an opening which passes transversely through the 30 tray and having its other end spaced above the upper surface of the tray, a water tank mounted upon the tray and located within the heat zone of the flame of the burner,

a tube disposed through the upper side of the goose-neck member and having its discharge end disposed above the upper surface of the tray and within the end portion of the goose-neck member which is spaced from the tray and constituting the 35 point of combustion, a pipe connecting the tube with the water tank, and an oil pipe connected with the tube at a point above the 40 goose-neck member.

2. A burner comprising a tray, a goose-neck member communicating at one end 45 with an opening which passes transversely through the tray and having its other end spaced above the upper surface of the tray, a tank mounted upon the tray within the heat zone of the flame of the burner, a tube 50 disposed through the upper side of the goose-neck member and having its discharge end spaced above the upper surface of the tray, a pipe connecting the tube with the tank, and a nozzle passing transversely 55 through the upper side of the goose-neck member and surrounding the discharge end of the said tube and spaced from and having its lower end disposed below the lower end of the said tube, and means for admitting oil into the upper end of the said nozzle.

In testimony whereof I affix my signature.

ERNEST S. HOYT.
